UNITED STATES PATENT OFFICE.

GEORGE H. LELAND, OF DAYTON, OHIO, ASSIGNEE OF ONE-HALF TO THE LELAND ELECTRIC COMPANY, OF DAYTON, OHIO, A CORPORATION OF OHIO.

DYNAMO-ELECTRIC MACHINE.

Application filed November 22, 1920. Serial No. 435,832.

This invention relates to improvements in dynamo-electric machines, having special reference to single-phase alternating current motors of the repulsion-starting and induction-running type.

In single-phase, alternating current motors, the straight repulsion type without compensating windings produces, as is well known, the most satisfactory starting characteristics, while the induction type with completely short-circuited armature or rotor windings produces the best operating characteristics aside from starting. These known conditions have led to the production of the repulsion-starting, induction-running motor, in which the armature currents are secondary and which, while the motor is in starting speed, flow through a commutated short-circuit and, as the motor approaches operating speed, the armature coils are automatically short-circuited in parallel and the secondary currents are no longer commutated.

In short-circuiting devices heretofore used in motors of this character it has been the practice to use a centrifugal element mounted relative to the armature shaft and having its force generated by the speed of the motor to actuate the short-circuiting mechanism. Various movements, both rotary and axial and a combination of both, have been employed to effect contact of the short-circuiting element with the commutator to establish and disrupt the short circuit of the armature.

The object of the present invention is to provide improved short-circuiting mechanism for repulsion-induction motors of the type above referred to whereby simplicity of construction and the highest efficiency of operation, both in starting and running, will be realized.

In the present invention also I have used a centrifugal element mounted relative to the armature shaft to control the short-circuiting element, but I employ an outwardly directed, radial movement of both elements to establish the short-circuit, and an inwardly directed, radial movement to disrupt the same, as distinguished from the devices of earlier construction above referred to.

The construction of the present invention is simpler and more economical than what is common to short-circuiting devices of this character,--also there is increased efficiency

of operation due to a positive wiping contact between the short-circuiting element and the commutator which acts to keep the contact surfaces clean and therefore to form more effective contact relations therebetween. Furthermore, the wiping action of the contact surfaces minimizes the tendency to create a spark when contact is made or broken. While I do not claim broad novelty relative to wiping contacts, the construction here shown is nevertheless of an improved and highly effective character.

Other objects and advantages realized in my invention will be apparent from the accompanying drawings and the herein detailed description thereof.

In the drawings:

Fig. 1 is an end elevation of the commutator of a repulsion-induction motor having my improved short-circuiting mechanism applied thereto, a portion of the mechanism being broken away to better show the relation of the parts;

Fig. 2 is a detail sectional view taken on the line 2-2 of Fig. 1, and showing the parts in idle or normal inoperative relation;

Fig. 3 is an enlarged double detail sectional view showing parts in relative relations at different steps of the short-circuiting operation;

Fig. 4 is a diagrammatic view showing the direction of forces developed in the short-circuiting operation.

The details of motor construction here shown to illustrate the invention consist of the armature shaft 1, rotor 2, commutator ring 3 and segments or bars 4. These parts are common to motors of this type and may be of any suitable construction.

The short-circuiting mechanism of the present invention consists in the form shown in Figs. 1, 2 and 3 of a series of wedge-shaped weights 5 arranged circumferentially relative to the armature shaft and adapted to be moved outwardly, radially of the shaft, by centrifugal force as the motor attains speed. When the motor is at rest the weights are held in their normal inoperative relation by a circumferentially arranged tension element 6 which engages the outer ends of the weights and presses the same inwardly with their inner ends contacting with a sleeve projection 8 of a weight retaining plate 7 arranged telescopically of the armature shaft 1. The outer face of the weights

5 has sliding contact with the plate 7, the inner face of the weights having a lower inwardly extended projection 9 which has sliding contact relation with the lower portion 5 of the outer face of the commutator ring 3, and an upper inwardly extended projection 10 which has sliding contact relation with the upper portion of the face of the commutator ring and with the outer ends 10 of the commutator segment bars 4. Thus the weights have sliding contact at three points which provides suitable support for their operation.

As shown in Fig. 1, the weights 5, in their 15 inoperative relation rest with their tapered lateral edges in contact one with another, thus forming a disc made up of the series of weight units. Actuated by centrifugal force generated by the speed of the motor, 20 the weights move outwardly, substantially radially, against tension element 6, thus bringing the projections 10 into sliding contact with the ends of the commutator segments, the spring acting to check or restrain 25 the centrifugal force of the weights and thus to control their movement according to the speed of the motor. The tension element 6 is preferably in the form of a contractile band and is here shown as an annular helical spring, that is, a helically wound spring having its ends connected one to the other to form an endless band or garter spring. Such a spring is peculiarly adapted 30 to this purpose because it expands uniformly and the convolutions thereof separate as the spring expands and thus remain in substantially the same positions with relation to the respective weights in all positions of the short circuiting element. Consequently 35 there is little or no friction between the spring and the weights. Further, due to the round or circular cross section of the contractile band it readily rolls up or down the inclined margins of the weights as need be, always maintaining a more or 40 less uniform pressure between itself and the retaining member and between the contact weights and the commutator. Compared with a contractile band of the clock spring type or of the overlapping spiral band type 45 the helically wound spring is extremely flexible, permitting it to shape itself to conform to various positions of the weights, commutator and retaining plate but always 50 maintaining equalized pressure between the respective parts.

As best shown in Fig. 3, the outer ends of the weights 5 are beveled inwardly toward plate 7. Thus spring 6 is disposed within 55 the angle formed between the bevel of the weights and the inner face of plate 7, the spring contacting firmly with both surfaces and acting to press the projections 10 of the weights into contact with the commutator segments with increasing force as the

weights move outwardly,—the direction of forces employed being illustrated diagrammatically in Fig. 4 in which A indicates the direction of the centrifugal force exerted on the weights, B the direction of resistance 70 exerted on the weights by the spring, and C the direction of force exerted on the weights at their contact points.

The sliding contacts made by the weights with the commutator segments effects what 75 is commonly known in this art as "wiping contact" as distinguished from contacts made with a reciprocal movement of the contact elements. The wiping action of the contact elements as here shown serves to 80 keep the contact surfaces clean and thus to effect better circuit relations, it also minimizes the tendency to create a spark when contact is made or broken,—thus increased 85 efficiency of operation of the motor is realized.

Operation of the motor, having particular reference to the short-circuiting mechanism, briefly stated, is as follows: When the 90 motor is at rest the centrifugal weight elements are in their innermost position. In starting, the motor operates by repulsion the weights being moved outwardly by centrifugal force as the motor attains speed until contact is made with the commutator, when short-circuiting of the armature is effected and the motor operates by induction. When the motor falls below operating speed 95 the centrifugal force generated by the weight elements abates and the weights under the influence of the resistance spring are retracted, thus breaking the contact with the commutator and disrupting the short-circuit when the motor will again change automatically 100 for operation by repulsion.

I regard my invention broadly as a radical departure in principle and construction from short-circuiting devices of this character heretofore made, having particular reference to the spring-restrained, radially movable weight elements whereby contact with the commutator is made and broken to effect and disrupt respectively short-circuiting of the armature, and the inclined surfaces which act to exert radial pressure on the spring whereby increased force is exerted on the short-circuiting element as final contact is made with the commutator, thus increasing the effectiveness of the wiping action of the contact surfaces and of the circuit thereby established. The principle 115 of the invention as broadly and specifically applied in these particulars is defined in the appended claims.

Having described my invention, I claim:

1. A short-circuiting device for electric motors, including in combination with a commutator, a plurality of weight elements arranged circumferentially and operable radially relative to the axis of rotation of the 120

- commutator, a contractile tension element supported by and co-acting with the outer ends of said weight elements to restrain the radial movement thereof and acting further on said elements to cause the same to form contact relation with the commutator under pressure. 5
2. A short-circuiting device for electric motors, including in combination with a commutator, a plurality of weight elements arranged circumferentially and operable radially relative to the axis of rotation of the commutator, a contractile band supported by and co-acting with the outer ends of said weight elements to restrain the radial movement thereof and acting further to exert lateral pressure on said elements to cause the same to effect wiping contact with the commutator. 10
- 20 3. A short-circuiting device for electric motors, including in combination with a commutator, a plurality of weight elements arranged circumferentially and operable radially relative to the axis of rotation of the commutator, a tension element co-acting with the outer ends of said weight elements to restrain the radial movement thereof and acting further on said elements with gradually increasing lateral pressure thereon to cause said elements to effect wiping contact with the commutator. 25
4. A short-circuiting device for electric motors, including in combination with the commutator, a short-circuiting element consisting of a series of segmental weights, having inclined outer ends, arranged circumferentially of and slidable radially relative to the motor shaft through centrifugal action to engage the commutator to effect short-circuiting of the motor, and a circumferentially arranged tension member in engagement with said inclined ends and acting to restrain outward movement of the weights and to force the same against the commutator with increasing pressure. 30
5. A short-circuiting device for electric motors, including in combination with the commutator, a short-circuiting element consisting of a series of segmental weights, having inclined outer ends, arranged circumferentially of the motor shaft and slidable radially through centrifugal action into engagement with the commutator to effect short-circuiting of the motor, and a circumferentially arranged tension member in engagement with all of said weights and acting to restrain the same in said slidable movement. 35
6. A short-circuiting device for electric motors, including in combination with the commutator, a short-circuiting element consisting of a series of segmental weights, having inclined outer ends, arranged circumferentially of the motor shaft and slidable outwardly through centrifugal action into wip- 40
- ing engagement with the commutator to effect short-circuiting of the motor, and a circumferentially arranged tension member in engagement with said inclined ends and acting to restrain said sliding movement of the weights and to force the same against the commutator with increasing pressure as said wiping engagement is made therewith. 70
7. A short circuiting device for electric motors including in combination with a shaft and a commutator carried thereby, a centrifugal element comprising a plurality of weights arranged circumferentially of said shaft, movable outwardly by centrifugal force and having their outer ends beveled, and a contractile spring element supported by and cooperating with the beveled ends of said weights, one of said elements being electrically conductive and adapted to be moved into short circuiting contact with the commutator, whereby said contact is made with increasing the pressure as the weights move outwardly. 75
8. A short circuiting device for electric motors comprising in combination with a shaft and a commutator carried thereby, a centrifugal element comprising a plurality of weights arranged circumferentially of said shaft and movable outwardly by centrifugal force, a spring element arranged circumferentially of and movable outwardly with said weights and arranged to exert resistance thereon at an angle to said outward movement, to resist said outward movement and to press one of said elements into contact with said commutator. 80
9. A short circuiting device for electric motors including in combination with a shaft and a commutator carried thereby, a retaining member supported by said shaft and spaced from the face of said commutator, a series of weight elements arranged circumferentially of said shaft between said retaining member and said commutator and movable outwardly by centrifugal force, each of said weight elements having its outer end inclined toward said shaft and said retaining member, and an annular contractile band engaging the inclined outer ends of said weight elements and said retaining member to press said weight elements toward said commutator and to resist their outward movement by centrifugal force. 85
10. A short circuiting device for electric motors including in combination with a shaft and a commutator carried thereby, a retaining member supported by said shaft and spaced from the face of said commutator, a series of weight elements arranged circumferentially of said shaft between said retaining member and said commutator and movable outwardly by centrifugal force, each of said weight elements having its outer end inclined toward said shaft and said retaining member, and an annular helical spring 90
- 110
- 115
- 120
- 125
- 130

- engaging the inclined outer ends of said weight elements and said disk to press said weight elements toward said commutator and to resist their outward movement by centrifugal force. 5
11. In a short circuiting device for electric motors, a series of commutator bars to be electrically interconnected, a disk arranged in fixed spaced relation with said series of 10 commutator bars, an annular series of centrifugally controlled contact members interposed between the commutator and disk, and spring means arranged between said commutator and said disk and acting on said 15 weights to press the same against said commutator and exerting pressure on said disk in a direction away from said commutator. 12. A short circuiting device for electric motors including in combination with a commutator, a plurality of weight elements arranged circumferentially of the axis of said commutator and movable outwardly by centrifugal force, and an annular helical spring arranged circumferentially of said weight 20 elements and engaging the outer ends thereof to resist the outward movement of said weight elements by centrifugal force. 13. A short circuiting device for electric motors comprising, in combination with a commutator, an annular series of weight elements arranged concentrically with the axis of said commutator and movable outwardly by centrifugal force, and a contractile band in rolling engagement with said weight elements and adapted to exert resistance to the 25 outward movement thereof. 14. A short circuiting device for electric motors comprising in combination with a commutator a retaining member mounted in spaced relation to said commutator, an annular series of weight elements interposed between said commutator and said retaining member, arranged concentrically with the axis of said commutator, movable outwardly by centrifugal force and having portions inclined to the axis of rotation of said commutator, and a contractile band interposed between said commutator and said retaining member, arranged to have rolling engagement with the inclined portions of said 30 weights and serving to restrain the outward movement of said weights and to maintain them in yieldable contact with said commutator. 15. A short circuiting device for electric motors comprising, in combination with a commutator, an annular series of centrifugal weight elements arranged concentrically with the axis of said commutator and movable outwardly by centrifugal force, and a contractile band arranged in engagement 35 with said weight elements, adapted to expand uniformly throughout its length and arranged to simultaneously resist the outward movement of said weight elements, maintain the same in yieldable contact with the commutator as they move outwardly and maintain each weight element in a substantially radial position with relation to the axis of said commutator. 65 70
16. A short circuiting device for electric motors comprising, in combination with a commutator, an annular series of weight elements arranged concentrically with the axis of said commutator and movable outwardly by centrifugal force, and an annular helical spring supported in rolling engagement with said weight elements and arranged to exert pressure thereon at an angle to said radial movement. 75 80
17. In a short circuiting mechanism for electric motors, a series of commutator bars to be electrically inter-connected, a disk mounted in spaced relation with said series of commutator bars, an annular series of centrifugally controlled contact members interposed between the commutator and disk, an annular helical spring interposed between said commutator and said disk and in rolling engagement with said series of contact elements, said spring being adapted to re-act upon the disk and to simultaneously resist the outward movement of said contact members and maintain them in yieldable sliding contact with the face of the commutator. 85 90 95
18. In a device of the character described, the combination with a commutator and a retaining member mounted in spaced relation one to the other, said commutator comprising a core and contact bars carried thereby of cooperating weight and spring elements interposed between said commutator and said retaining member and cooperating to maintain continuous frictional engagement with both the retaining member and the commutator. 100 105
19. A short circuiter for electric motors, including in combination with a commutator, a plurality of weight elements arranged circumferentially of the axis of the commutator and movable under centrifugal influence to effect the short circuiting of said commutator, and a helical spring, the ends of which are interconnected into an annular band, said spring having engagement with exterior margins of the weight elements and against the yielding resistance of which the weight elements move under centrifugal influence to effect short circuiting of the commutator. 110 115 120

In testimony whereof, I affix my signature.
GEORGE H. LELAND.
